UNITED STATES PATENT OFFICE

166,401

ANIMAL HALTER

Gus Mackie, Bellevue, Wash.

Application August 18, 1950, Serial No. 11,825

Term of patent 14 years

(Cl. D38—6)

To all whom it may concern:

Be it known that Gus Mackie, a citizen of the United States, residing at Bellevue, Washington, has invented a new, original, and ornamental Design for an Animal Halter, of which the following is a specification, reference being had to the accompanying drawing, forming a part thereof, in which

Figure 1 is a perspective view of an animal halter, showing the essential features of my new design, in full lines;

Figure 2 is a side perspective view of the connector ring only, but on a larger scale for the purpose of bringing out more clearly the details thereof;

Figure 3 is a side elevational view of the opposite side as shown in Figure 2;

Figure 4 is a cross-sectional view taken along line 4—4 of Figure 3; and

Figure 5 is a cross-sectional view taken along line 5—5 of Figure 3.

I claim:

The ornamental design for an animal halter, as shown and described.

GUS MACKIE.
